UNITED STATES PATENT OFFICE.

JOHN COOPER, OF NEW YORK, N. Y.

DESIGN FOR A CHIMNEY-CAP MEMBER.

SPECIFICATION forming part of Design No. 32,362, dated March 20, 1900.

Application filed January 24, 1900. Serial No. 2,690. Term of patent 14 years.

To all whom it may concern:

Be it known that I, JOHN COOPER, of the city of New York, borough of Brooklyn, in the county of Kings and State of New York, have 5 invented and produced a new and original Design for a Chimney-Cap Member, of which the following is a full, clear, and exact description.

Reference is to be had to the accompanying drawing, forming a part of this specification, in which the figure of the drawing is a perspective view of a chimney-cap member, showing my design.

My design for a chimney-cap member consists in a body portion of a rectangular outline in which an opening is shown, and on an upper side edge of the body portion an outwardly-extended flange is shown, the under

side of which is on a parallel plane with the top surface of the body portion. 20

Referring particularly to the drawing, it will be seen that the opening through the body portion is rectangular and that the flange is transversely rounded on its upper side.

Having thus described my invention, I 25 claim as new and desire to secure by Letters Patent—

The design for a chimney-cap member, as herein shown and described.

In testimony whereof I have signed my 30 name to this specification in the presence of two subscribing witnesses.

JOHN COOPER.

Witnesses:

JNO. M. RITTER,
C. R. FERGUSON.
